Specification for Design.

Patented Dec. 13, 1921.

Application filed August 12, 1918. Serial No. 249,583. Term of patent 14 years.

To all whom it may concern:

Be it known that I, ARTHUR O. AUSTIN, a citizen of the United States, residing at Barberton, in the county of Summit and State of Ohio, have invented a new, original, and ornamental Design for Insulators, of which the following is a specification, reference being had to the accompanying drawing, forming part thereof.

In the accompanying drawing, Figure 1 is a side view of an insulator embodying my

new design, Fig. 2 is a another side view to an angle different than that in Fig. 1, and Fig. 3 is an end view of the insulator.

I claim:

The ornamental design for an insulator, as shown.

ARTHUR O. AUSTIN.
